TREATMENT OF FLUIDS

Arthur E. Pew, Jr., Bryn Mawr, Pa., and Raymond C. Lassiat, Woodbury, N. J., assignors, by direct and mesne assignments, to Houdry Process Corporation, Wilmington, Del., a corporation of Delaware

Application February 18, 1936, Serial No. 64,488

3 Claims. (Cl. 196—52)

The present invention relates to the art of treating fluids and to process and apparatus therefor. It has particular application to processes of the type where temperature control, especially close or fairly accurate temperature control, is necessary or desirable, as in many contact or catalytic processes and particularly, for example, in the contact or catalytic treatment or conversion of hydrocarbons, whether derived from petroleum, coal, shale or other origin, natural or artificial, although other reactions, such as catalytic oxidations, hydrogenation of organic materials, etc., are of course contemplated. The invention further relates to the use of a medium in the temperature regulation of the operation, such as steam, various condensable or incondensable gases, or other inert or different fluids, which it is desired to add directly to the fluid to be treated to improve or foster the reaction. Operations with contact masses or catalysts which become contaminated or coated with deposits during reaction and accordingly are arranged to be alternately on-stream and in regeneration, are among those contemplated.

While the temperature of the treating or contact operations may be controlled in many ways, to make suitable or accurate control available in a practicable sense, it is necessary that the control be effected in an economical as well as in a suitably accurate manner. Large or excessive expense for temperature control may, for example, be encountered where a temperature regulating fluid must be heated to a high temperature, only reduced in temperature a small amount to maintain an endothermic reaction at a slightly lower temperature, and then is merely fed through heat exchangers or to waste heat boilers or the like. It is further desirable that the system of temperature control have flexibility of operation; otherwise the investment cost for treating apparatus in a plant, for example, for refining petroleum, coal or fractions of either, will, in some cases, be so high or excessive as to render non-feasible the operations requiring such a degree of temperature regulation.

It is an object of this invention to devise a system of temperature regulation and suitable apparatus for carrying out the same which will provide for economy in temperature control and flexibility in operation. It is also an object of this invention to supply inert diluent or other fluid, which it is desired to introduce with the reactants, in an economical manner, preferably by using a temperature regulating medium such as process steam which can also be employed as

the fluid to be added with the reactants. Another object of this invention is to make the system of temperature control readily applicable to one, a battery, or any plurality of converters or treating chambers. Other objects include: employing a temperature regulating medium as a cooling fluid to control an exothermic reaction and then, by virtue of the heat picked up in the cooling operation, with or without further exchange of heat as may be necessary, using it as a heating fluid to control an endothermic reaction; employing an inert fluid for three purposes, viz. (1) as a cooling fluid, (2) as a heating fluid, and (3) as process steam or equivalent; adding fluid to or subtracting it from the stream of temperature regulating medium as it passes from one converter or case to another, as desired; effecting the desired temperature control whether one, two or more or all of the converters or cases are on-stream at the same time or vice versa, on regeneration at the same time, whether it is desired to have each of the several converters at similar or at differing temperatures, by passing the temperature control medium in parallel or series or partly in parallel and partly in series through the plurality of converters; and effecting circulation of the temperature control fluid with a minimum of pumps.

The above and other objects and advantages will appear from the subsequent description taken in connection with the accompanying drawings in which:

Fig. 1 shows a single converter in vertical section together with apparatus and connections for supplying a temperature regulating fluid, i. e. a heating or cooling fluid, thereto and for employing a part or all of it as process fluid;

Fig. 2 shows a plurality of converters in elevation and one partly in section, together with apparatus and connections for passing a temperature regulating fluid therethrough, in series or not, as desired; and

Fig. 3 shows a plurality of converters as in Fig. 2 but with connections especially arranged and adapted for operation on cycle, i. e. one or more on-stream while the other or others are in regeneration, together with apparatus for passing hot (or cool) fluid through either while cool (or hot) fluid is passed through the other.

In the following discussion, by way of definite illustration, a composite hydrocarbon fluid, specifically a fraction or fractions of petroleum, will be considered as being treated. Also water or steam will be taken as the temperature regulating medium, although obviously various other

heating or cooling media, particularly fluids which boil at a temperature so that their latent heats of vaporization could be utilized in the temperature regulation, such as propane and/or butane or the like, could be employed; also fluids such as CO₂, N₂ and H₂ can be used as temperature regulating media. Likewise, various fluids other than petroleum fractions could be acted upon or treated, e. g. other composite hydrocarbon fluids, organic fluids, or inorganic fluids.

Referring in detail to the drawings, in the figures of which like reference characters denote similar parts, 1 is a converter surrounded by insulation 2 and having a reaction chamber in 15 which extend conduits 3, which may be considered as inlet conduits for reactants, and conduits 4, which may be considered as outlet or withdrawal conduits for the products of the reaction. These groups of conduits are provided with 20 perforations or openings 5 and 6, respectively, which are distributed throughout the length of each. Surrounding these conduits within the reaction chamber is a suitable contact mass 7 which may comprise or include various materials which cover 25 the range from those which are inert or substantially inert to those which are highly catalytic to the reaction which is to be performed within the reaction chamber. The contact mass may consist of any known or desired material, but is preferably in the form of fragments or molded pieces which are readily susceptible of regeneration in situ. In a number of operations for the refining and conversion of petroleum hydrocarbons, activated hydrosilicate of alumina and blends of 30 silica and alumina of controlled ratio, either natural or artificial, in the form of small molded pellets or cylinders, either solid or hollow, and with or without the addition of other catalytic materials, such as metals or metallic compounds, 35 have been used with advantage.

Reactants, which may consist of a fraction of petroleum to be treated or converted, may be introduced into the converter 1 through heater 8 and atomizer 9 by means of pump 10. The atomizer 9 is optional and may be by-passed or dispensed with where the temperature employed and the nature of the fluid do not make atomization necessary or desirable. The heated fluid is introduced into manifolding chamber 11 of the converter 1 and from there enters conduits 3 and passes therefrom through openings 5 therein, thereby being distributed throughout the reaction chamber and brought into contact with the bed of contact mass or catalyst 7. The products of reaction enter conduits 4 through openings 6 therein and, by means of conduits 4, pass from the reaction chamber into manifolding chamber 12 of the converter. From manifolding chamber 12 the reaction products may pass from the converter through the line controlled by valve 13 and thereby be led to storage or to any additional treating apparatus, as desired.

After the reaction has continued for a suitable period of time, depending upon the nature of the particular reaction, the contact mass 7 may become poisoned or contaminated by deposits which are usually burnable and require regeneration or removal of such contaminants in order to restore it to a state of desired activity. This 50 may be done by stopping the introduction of reactants and by closing valves 14 and 13. Gases or fumes may be removed from the converter by use of vacuum purging or purging with steam, flue gases or other methods of purging understood by those skilled in the art. Following

purging a regenerating medium such as air or other oxygen-containing gas may be introduced into manifolding chamber 11 of the converter through line 15, controlled by valve 16 and after following the same paths through the converter that were followed by reactants and reaction products, the products of regeneration or the regeneration fumes may be withdrawn from manifolding chamber 12 of the converter through line 17, controlled by valve 18.

In many (but not all) cases of contact or catalytic conversion or refining of hydrocarbon fractions, the converting or transforming operation is an endothermic reaction which tends to cause the temperature of the reaction chamber and of the contact mass to drop, while the regeneration step is usually exothermic in character, tending to cause the temperature of the reaction chamber and of the contact mass to rise. In such reactions it is essential to keep 20 the temperature of the reaction chamber during the on-stream or transforming portion of the cycle within certain limits and often relatively narrow limits in order to get an efficient conversion or treatment. Similarly, during the exothermic regeneration, it is necessary to control the temperature of the reaction chamber and the contact mass 7 within a predetermined temperature range in order to get an efficient regeneration and to avoid injury to the contact 30 mass or catalyst. The present invention provides apparatus in combination with the converter 1 whereby heat may be added to the reaction chamber during the endothermic reaction and heat may be withdrawn from the reaction 35 chamber during the exothermic conversion.

During the on-stream or conversion period an inert fluid, such as steam, may be introduced through conduit 19, controlled by valve 19a and forced by pump 20 through heater 21, wherein any desired additional amount of heat may be added, and thence through a duct controlled by valve 22 into the tubular manifolding header 23 located within manifolding chamber 12 but out of fluid communication therewith.

From manifolding header 23 the inert fluid or steam may pass through the U-tubes 24 located within conduits 4 and, after giving up heat to the walls of conduits 4 and to the surrounding contact mass 7 by radiation and conduction, 50 pass into tubular manifolding header 25 and pass from the latter through the line controlled by valve 26. After passing through valve 26, the steam which is ordinarily still at a temperature as high as or slightly higher than that of 55 the reaction, may be passed through line 27, controlled by valve 28 to mingle with the reactants and to be utilized, if desired, in atomizer 9 to assist in the atomization of the reactants and to increase their temperature slightly. 60 When atomizer 9 is not employed, steam may be introduced into the line between the heater 8 and manifolding chamber 11 of the converter. In addition to or in lieu of introduction at such point, the steam may be passed through line 65 29 controlled by valve 30 and be introduced with the reactants at one or more points before and during their passage through the heater 8 under control of valves 31 and 32, for example. Some introduction of steam or equivalent at 70 such points may be necessary or desirable to hold thermal cracking to a minimum. In passing through line 29 the steam may be cooled or have its temperature adjusted to any desired extent by passing through temperature regula- 75

tor 33 or it may be by-passed therearound in whole or in part through the line controlled by valve 34.

When the flow of reactants is cut off to give time to effect a regeneration of the contact mass 7, purging of the converter may be effected by passing the steam through line 27 into manifold chamber 11 and from manifolding chamber 12 of the converter out through line 17, controlled by valve 18, for example.

When regeneration is begun, as above described, valves 22 and 26, inter alia, will be closed and valves 35 and 36 will be opened. Cooling fluid such as water may be introduced through line 37, controlled by valve 38, and be forced by pump 39 into manifolding header 23. From the latter the water or equivalent temperature regulating fluid will pass through U-tubes 24, emerge therefrom into manifold 25, and pass from the latter through valve 36 to cooler 40, from which latter the heat regulating fluid will pass as water (or low temperature steam, as desired) and may be recycled by pump 39. Where some steam is desired in admixture with the air or other regeneration fluid, the same may be withdrawn from the line 41, preceding the cooler, and be passed through line 42, controlled by valve 42a into line 15.

It will be noted that the apparatus shown in Fig. 1 illustrates separate systems for supplying heating and cooling fluids, such as steam and water respectively, and also illustrates the use of the temperature controlling medium, i. e. heating or cooling fluid, as fluid which may be introduced with the reactants or regeneration medium to improve the reaction or regeneration. This type of operation is particularly applicable when it is desired to add additional fluids, such as high temperature steam, to the reactants in order to maintain them in vapor phase or otherwise to improve the reaction, although in some cases it is advantageous to supply steam or equivalent with the air or other regeneration medium.

In Fig. 2 much of the apparatus shown will be readily understood in view of Fig. 1 and the detailed description thereof given above. Reactants may be introduced into either converter 1a or 1b by forcing the same through heater 8a by means of pump 10a. In passing to converter 1a the fluid flows through line 45 controlled by valve 45a, while in passing from heater 8a to converter 1b fluid passes through line 46 controlled by valve 46a, thence through line 47, controlled by valve 47a, and finally through valve 48a into converter 1b. Reaction products pass from converter 1a through line 49, controlled by valve 49a and from converter 1b through line 50 controlled by valve 50a. Also, reactants may be introduced into converter 1b or converter 1a by forcing the same through heater 8b controlled by pump 10b. In passing from heater 8b to converter 1b the fluid passes through line 48 controlled by valve 48a, while in passing from such heater to converter 1a fluid passes through line 48, thence through line 47, controlled by valve 47a, thence through line 46, controlled by valve 46a, and finally through valve 45a into converter 1a.

Converters 1a and 1b may both be operated on-stream at the same time on similar or different reactants, or both may be on regeneration at the same time, or one may be on-stream and one on regeneration at any particular time. One converter may be used, for example, to effect a mild cracking or viscosity breaking of heavy hy-

drocarbons such as those comprising or containing a residue from a distillation such as a very heavy gas oil or tar for the purpose of converting such material into a form so that a substantial part of it is in the range of a good charging stock for a cracking reaction, e. g., in the light gas oil range. Then this resultant material may be passed through the other converter to produce gasoline therefrom. One converter can be used for the heavy material and the other or remaining one be used to complete the transformation of the partially converted or lighter material. In short, the converters may be used in series or in parallel on the same or on different charging stocks. The above discussion as to the way reactant fluids may be introduced and treated is given by way of illustration only because the invention is concerned principally with the matter of temperature control of such reactions or their equivalent.

Let us imagine the situation where converter 1a is undergoing an exothermic regeneration (or reaction) at a temperature within a range of the order of 900 to 1200° F. and converter 1b is being used to carry out an endothermic or on-stream reaction at a temperature of the order of 750° to 950° F. A relatively cool fluid, such as water at a temperature of 60° to about 300° or 400° F., depending upon pressure, may be introduced through line 51 controlled by valve 51a and forced by pump 52 through line 53, controlled by valve 53a or through heat exchanger or cooler 21a through valve 51b into tubular manifold 23a and thence through U-tubes 24a extending within conduits 4. The fluid emerges from the U-tubes 35 into tubular manifold 25a, usually in the form of steam at a temperature of the order of 212° to 800° F., depending upon the pressure, and may be passed through heat exchanger 54 where a further change or increase in temperature is effected, as desired, and then is sent at a temperature of about 50° to 250° F. higher than the reaction temperature, i. e., 800° to 1200° F., through duct 55 into the heat exchange ducts of converter 1b. From the latter the steam, at a reduced temperature of about 25° to 225° F. below that of the steam sent into converter 1b, passes through duct 56, duct 57 controlled by valve 57a, back to duct 51 behind the pump 52 and from there may be again recycled through the heat exchange system of the converters.

Any desired proportion of the steam emerging from converter 1b through line 56 may be passed through duct 58 and introduced with the reactants, prior to their entrance into heater 8a, by passing through line 63 and valve 59a or, during their passage through heater 8a, by introduction through valve 60a; likewise, steam may be introduced into reactants before they enter heater 8b by passage through valve 59b or, during their passage through heater 8b, by introduction through valve 60b. If it is desired to pass steam from duct 56 into the reactants subsequent to their passage through either heater 8a or 8b or both, steam may be passed through valve 46b in line 46 and from the latter introduced into the reactants entering either one or both of the converters shown by an obvious adjustment of valves.

In the case that it is preferred to use steam of the temperature of that emerging from converter 1a, the same may be withdrawn through line 61, controlled by valve 61a, and then passed therefrom through branch 62 into duct 63. From duct 63 the steam or equivalent may be introduced

with the reactants either prior to or during their passage through either heater 8a or heater 8b. If it is desired to pass steam from duct 61 into the reactants subsequent to either or both heaters, steam may be withdrawn from duct 61 through branch 65, controlled by the valve as shown, into line 46. From the latter, steam may be passed through line 45 to converter 1a or through lines 47 and 48 to converter 1b.

10 When converter 1a is on-stream with an endothermic reaction, and converter 1b is undergoing regeneration or an exothermic reaction, heat exchange fluid admitted through line 51 may be heated in heat exchanger 21a and, following 15 emergence from heat exchange with converter 1a, the fluid may be cooled in heat exchanger 54, as desired, before passing through and in heat exchange with the reaction zone of converter 1b. Otherwise, the operation of the temperature 20 control system is very similar to and understandable from the description above given where we imagined converter 1a undergoing an exothermic reaction and the converter 1b an endothermic reaction. Where a very large proportion of the 25 steam or equivalent heat exchange fluid is withdrawn through duct 61 to be used as process steam, which may be as high as 50 to 70% or even sometimes 100%, the additional amount of aqueous fluid needed for exchange purposes in 30 converter 1b may be introduced into the circuit through duct 64, controlled by valve 64a. Heat exchange fluid emerging from 1b through line 56 may also be employed in whole or in part as process steam or may be recirculated through line 57 and valve 57a back to the line leading to converter 1a.

Where there are two or more converters, each of which is on a different exothermic reaction than another or others thereof, e. g. one converter is on exothermic reaction at a temperature of the order of 500° or 600° F. and another is on an exothermic regeneration at a temperature of the order of 900° to 1200° F., the temperature regulating fluid may be passed into heat exchange 45 with the converter undergoing the low temperature reaction in a range of the order of atmospheric to 200° F. or so and may be passed therefrom at a temperature of the order of 200° to 400° F., into heat exchange with the converter undergoing regeneration at the higher temperature. The latent heat of vaporization of the temperature regulating fluid is usually and preferably employed in the more strongly exothermic reaction, which, in this case, is ordinarily the 50 regeneration.

One example of two or more converters operating on different endothermic reactions is the case where one or more converters are employed in a catalytic cracking or conversion at a temperature of the order of 840° F. and another or others are employed in the catalytic reforming of naphtha at a temperature of the order of 850° to 925° F. Only slight temperature adjustment of the temperature regulating fluid is required 60 in passing from one converter to another converter which is undergoing a different endothermic reaction.

As above pointed out, the matter of supplying temperature regulating fluid to each converter at the respective temperature desired, without having to do more than to make an adjustment of temperature of the fluid in passing from one converter to another, is of great importance from the angle of economics, and is one of the objects 70 of the present invention.

The temperature control apparatus illustrated in Fig. 3 also provides for a high degree of flexibility in operation. It is most useful when one or a plurality of converters are being employed to carry out an endothermic reaction, 5 while another or others are being used to carry out an exothermic reaction. This apparatus may most readily be understood by resorting to illustration. First let us imagine the situation where converter 1c is in an exothermic regeneration and converter 1d is being used for an endothermic on-stream reaction. The - - - line indicates the circuit which the heat exchange or temperature regulating fluid may follow. It will be seen that relatively cool fluid is forced by pump 52c through line 70 into manifold header 23c of converter 1c from which it passes through the U-tubes 24c and then passes into the manifold header 25c, from which it may pass through line 71 through heater 72, where the temperature of 10 the steam or equivalent may be further increased. The steam then may pass through line 73 through the heat exchange apparatus within the converter 1d and then leaves such apparatus through line 74 from which it may pass through heat exchanger or cooler 75 and be recirculated through line 76 back to inlet duct 70 behind the pump 52c. Process steam or equivalent vaporizing or process fluid may be withdrawn from line 74 through line 77 to be admixed with reactants near the point 15 where they enter converter 1d or may be withdrawn through line 78 to be admixed with reactants as they pass through heater 79. Also process steam or the like, as it leaves converter 1c, 20 may be withdrawn through line 80 and introduced with reactants before they enter heater 79, or steam, after it has passed in heat exchange contact with the reaction chamber of converter 1d, 25 may be withdrawn through valve control lines 81 and 82 and introduced with reactants at the same 30 point preceding the heater 79.

Next let us take the case where converter 1d is in regeneration and converter 1c is on-stream and where the heat regulating medium passes first in heat exchange with converter 1d which 35 is undergoing an exothermic regeneration and then passes through converter 1c which is on-stream, undergoing an endothermic reaction. The path of flow of the temperature regulating medium is illustrated by the - - - - line. No 40 further discussion should be required to make clear how this type of operation is carried out, for, taken with the above paragraph and the flow lines, the operation is self-explanatory.

Next let us look at the situation where converter 1d is undergoing an exothermic reaction and converter 1c is undergoing an endothermic reaction but where it is desired to pass the temperature regulating medium first in heat exchange with converter 1c and then subsequently, 45 after suitable cooling or heat adjustment, passing it in heat exchange relation with converter 1d. The path of flow of the temperature regulating fluid is indicated by the - - - line and is practically self-explanatory. It will be seen that fluids 50 entering the circuit through valve 70a pass through line 88, then through heater 72 and line 83 to converter 1c. The fluid emerging from heat exchange with converter 1c passes through line 84 and line 85, and then through the cooler or 55 heat exchanger 75 and line 76 back into line 70 between valves 70b and 70c, the former of which is closed in this operation and the latter of which is open. The fluid then may flow through line 60 77 to converter 1d and be withdrawn from the 75

latter through valved duct 81 and be passed through line 82a back to heater 72, from which it may repeat the cycle. Process steam may be withdrawn from line 84 through line 81, passing 5 through either branch 81a or 81b, or may be withdrawn from line 84 through line 82 and valve 82v or through line 78 which is connected to line 14. Reactant fluid may be passed to heater 79 through duct 89 and preheater or heat exchanger 10 75 or directly through duct 90, as desired.

While the invention is described using two converters to illustrate a plurality, the operation is contemplated in connection with any plurality of converters or reaction chambers. It is obvious 15 that in place of passing steam or equivalent fluid through a single converter on-stream, as illustrated in Fig. 3, we may pass such fluid through any plurality of converters on-stream; likewise with those on regeneration.

20 It will be clear that Figs. 2 and 3 show very flexible types of temperature control apparatus. The temperature regulating medium may be passed in any succession through the several converters and a portion or all of it may be used 25 as process material, as desired. The matter of flexibility of operation of such a system is extremely important where a large investment must be made in a battery of converters and where periodical changes in the manner of using 30 the converters is necessary or desirable. For example, at one time it may be desired to employ one or a plurality of such converters to effect a viscosity breaking operation on heavy or tarry residual materials and another one or more of 35 such converters to further convert the viscosity broken products emerging from the first converter or converters. Again, it may be desired to use one or more of such converters to effect a catalytic cracking of a gas oil and to use another one or more of such converters to reform naphtha produced in such cracking operation or to refine some 40 or all of the products of such operation. Numerous other desirable variations in operation are encountered in petroleum refining practice. In 45 the absence of flexibility of operation of the temperature control system and method of providing for process steam or other fluid capable of fostering the desired treatment or conversion of reactants, the investment cost of apparatus would, 50 in effect be greatly increased, in that the apparatus would otherwise be only useful for a particular type or narrow scope of operations and duplication of apparatus would be necessary.

It is to be understood that, while treatment 55 or conversion of reactant fluids is, in the case of the fluids mentioned by way of illustration, often an endothermic reaction, in some cases the treatment or conversion of fluids is an exothermic reaction. Our invention, which concerns temperature control of reactions and supplying of fluid for fostering treatment or conversion of reactants, is not limited by the illustrations above given but has broad application to the control of reactions coming within the scope of the appended 60 claims, whether a single reaction or a plurality of similar or different reactions are involved and whether the different reactions are all endothermic, all exothermic, or partly endothermic and partly exothermic. The control of reactions herein described and illustrated is one which has broad application and provides substantial economies in operation and other advantages, as described.

What we claim is:

75 1. In chemical processes involving at least two

bodies of contact material which are used for simultaneously carrying out reactions having different temperatures of reaction, the method of operation and temperature control of the contact masses which comprises the steps of admitting reactants to the bodies of contact material in direct contact therewith to effect the reactions and withdrawing products of the reactions, continuously circulating a stream of extraneous heat exchange fluid serially through the bodies of contact material in indirect heat exchange relation therewith, increasing the temperature of said heat exchange fluid before passing it from one body to another body of contact material, decreasing the temperature of the fluid before again passing it to the first body of contact material, and admixing a portion of the heat exchange fluid with the reactants before admitting the reactants to the contact material.

2. In chemical processes involving a plurality 20 of bodies of contact material which are used for simultaneously carrying out alternate endothermic and exothermic reactions having different temperatures of reaction, the method of operation and temperature control which comprises 25 the steps of admitting reactants to each body of material to effect the reactions and withdrawing the resulting products of reaction, passing an extraneous fluid in indirect heat exchange relation with the bodies of material in continuous circulation first through the material undergoing the exothermic reaction at a temperature below 30 the temperature of the reaction in order to withdraw heat of reaction from the material and raise the temperature of the heat exchange fluid, supplying additional heat to further raise the temperature of the fluid and passing it in indirect heat exchange relation with the contact material which is undergoing the endothermic reaction at 35 a temperature above that of this reaction in order to supply heat to the reaction and lower the temperature of the fluid, then admixing a portion of the heat exchange fluid with a reaction fluid to the contact mass undergoing the endothermic reaction, and directing the remaining heat exchange fluid at its lowered temperature to the contact material undergoing exothermic reaction.

3. In the treatment or conversion of high boiling composite hydrocarbon fluid to produce lighter hydrocarbons having components in the gasoline boiling range in which a plurality of confined reaction zones, each containing an adsorptive catalytic mass in molded form and comprising a blend of silica and alumina, are employed, the said catalytic mass in each reaction zone being alternately on-stream to effect the desired conversion of reactants and in regeneration to effect removal of deposits of contaminants by combustion, one of said reaction zones undergoing regeneration while another is on-stream, said on-stream operation being an endothermic reaction carried out at a temperature of the order of 750° F. to 950° F. and at approximately atmospheric pressure and said regeneration being carried out at a higher temperature than the on-stream operation but not to exceed substantially 1200° F., the method of operation and temperature control which comprises passing reactant fluid into one of said reaction zones and withdrawing products of reaction therefrom, simultaneously passing an oxygen-containing regenerating fluid through another of said zones in which the catalytic mass is contaminated with combustible deposits from a previous on-stream reaction to burn such deposits 70 75 80 85 90 95

from the mass, continuously circulating an aqueous fluid serially, first through and in heat exchange with but out of fluid-communicating relation with the zone undergoing regeneration and
5 then with the zone which is on-stream, adding sufficient heat to said aqueous fluid in its passage from the said zone which is in regeneration to the said zone which is on-stream to bring the temperature of said fluid substantially above that
10 desired in the zone which is on-stream, introduc-

ing a portion of said aqueous fluid which emerges from heat-exchange relation with said zone which is on-stream into admixture with the said reactant fluid passing into the said zone which is on-stream and lowering the temperature of the 5 remaining aqueous fluid before again circulating it as a heat exchange medium.
